SWITCH OPERATOR

Carl W. Sundberg, Bloomfield Hills, and Montgomery
Ferar, Huntington Woods, Mich., assignors to Square D
Company, Park Ridge, Ill., a corporation of Michigan

Filed Nov. 23, 1960, Ser. No. 62,947

Term of patent 14 years

(Cl. D26—13)

FIG. 1

FIG. 2

FIG. 3

FIG. 4

FIG. 1 is a perspective view of a switch operator showing our new design;

FIG. 2 is a top plan view, to a reduced scale with the handle in another position;

FIG. 3 is a side elevational view, to a reduced scale, the opposite side being substantially a mirror image thereof; and

FIG. 4 is a front elevational view thereof, to a reduced scale.

Portions of the operating handle are shown in solid black and lined to indicate color. The essential features of our design are shown in full lines.

We claim:

The ornamental design for a switch operator, substantially as shown and described.
